UNITED STATES PATENT OFFICE.

GEORGE BAEHR, OF IRWIN, PENNSYLVANIA.

MULTIPLE-PART SEGMENTAL ROLL.

Application filed March 16, 1923. Serial No. 625,643.

To all whom it may concern:

Be it known that I, GEORGE BAEHR, a citizen of the United States, and a resident of Irwin, in the county of Westmoreland and 5 State of Pennsylvania, have invented a new and useful Improvement in Multiple-Part Segmental Rolls, of which the following is a specification.

This invention relates to composite rolls 10 for shaping metal bars and blanks. More particularly it relates to composite rolls having a permanent body member, and interchangeable segmental facing or forming members adapted to be arranged in parallel 15 cooperating series upon the roll body and clamped thereon.

The object of the invention is to provide forming segments so shaped and arranged that three or more parallel series of segments 20 cooperate, forming grooves being provided by the cooperating interfitting segments.

A further object is to provide segmental forming members adapted to cooperate in 25 three or more parallel series of segments, wherein an intermediate series of segments constitutes the bottom of a forming groove, the exposed faces of said intermediate segments having raised or sunken portions for 30 the purpose of forming indentations or projections in any desired form of configuration upon the side of a bar formed in the groove.

Another object is to provide in a composite roll comprising removable forming 35 segments a groove wherein the two sides and the bottom are formed respectively by separate removable segments.

Another object is to provide removable 40 forming segments in three or more cooperating pairs, so made that when the grooves formed by the segments have become worn, the faces of the segments may be machined off, the segments moved toward each other 45 to compensate for the loss, and the grooves re-dressed, without changing the dimensions of the forming grooves and without reducing the effective size of the roll.

Other objects and advantages will appear 50 to those familiar with the art from the following specification.

Referring to the drawings, Fig. 1 is a plan view and partial section of a roll embody-

ing one form of this invention, the roll being shown removed from its bearings; 55 Fig. 2 is a partial vertical section through a pair of cooperating rolls, taken on the line II—II of Fig. 1, in so far as the section of that roll is concerned; Fig. 3 is a partial section similar to that of Fig. 2, showing intermediate forming segments of slightly different form; Fig. 4 is a partial section similar to that of Fig. 2 showing segments for forming raised projections upon the bar; 60 Fig. 5 is a partial section showing a modified arrangement of segments adapted to form round and diamond shaped bars in two grooves formed by three segments; Fig. 6 is a modification showing three cooperating 65 series of segments adapted to roll a standard I-beam; Fig. 7 is a partial section showing an arrangement of segments adapted to roll a small rail; Fig. 8 is a partial longitudinal section through one of the rolls illustrated in Fig. 4; Fig. 9 is a modification 70 showing four cooperating series of segments forming three finishing grooves at their meeting edges; Fig. 10 is a modification of the arrangement for rolling standard I-beams as illustrated in Fig. 6, in that two intermediate segments are used instead of one, the single individual segment of Fig. 6 being 75 split in the middle; and Fig. 11 is a partial section showing the parts of Fig. 10 as they appear after having been re-dressed, and expanded by the addition of an intermediate ring.

In my prior Patent No. 1,289,602, there is described a composite roll comprising a permanent roll body adapted to receive removable forming segments, arranged in parallel series, with a forming groove at the meeting edges of the series of segments, and means for clamping the segments rigidly upon the roll body. 90

That roll has proved highly successful in practical operation, and the present invention comprises a roll of the same general character, the improvement lying in the provision of three or more cooperating segments, the intermediate segments being held 100 in place by overhanging portions of the outer segments, and the modification of the forming groove rendered possible by this construction. The present arrangement permits the rolling of products having two or 105

three plain faces, the other side having indentations or projections thereon such, for example, as gear teeth. It has, prior to this invention, not been practical to roll such shapes, since they required the forming of an irregular bottom to the groove, and that could only result from the casting of a solid roll having the irregular groove formed therein by the casting operation; or else by 10 expensive machining operations.

By the present invention I am able to machine the forming face of the intermediate segments without difficulty, as will be obvious to those skilled in the art, and then 15 by placing them between two outer series of segments having plain forming faces, a groove having straight sides and an irregular bottom is produced. Furthermore, when the groove has become worn I can remove and readily machine the outer segments, and the forming face of the intermediate segments, thus producing in effect 20 an entirely new groove, without changing the roll body at all. By this invention the 25 forming segments themselves may be made of high grade tool steel or the like, while the roll body may be made of much cheaper material, such as cast steel. These hardened tool steel forming segments will wear very 30 much longer, and may be re-dressed many times, thus reducing the cost of rolling special bars.

Referring to the drawings, in Fig. 1 there is illustrated a roll comprising a solid body 1, having the usual necks 2 and wobblers 3 at each end thereof for engagement with a proper housing and driving mechanism in the usual manner. It will be understood that although one roll is illustrated in this 40 figure, that a cooperating roll is understood, in operation mounted in a manner to contact with the one illustrated, in the usual parallel arrangement.

At one end of the roll body a fixed collar, 45 or raised abutment 4 is provided, and this has an inner undercut beveled face 5 as clearly illustrated. At the other end the roll body has formed thereon threads 6, and an internally threaded sleeve or nut 7 is 50 adapted to engage the threads 6 of the roll body, and to be turned down thereon, as illustrated at the right of Fig. 1. For the purpose of tightening or loosening this nut 7 on the roll, a brake band, extending 55 around the roll body and adapted to engage a groove 9 in the nut is provided. This brake band is fixed at one end as will be understood, and at the other end is attached to a screw 10, which extends through a 60 threaded hand wheel 11, rotatably mounted in some fixed part of the frame. Consequently by turning the hand wheel 11 the screw 10 may be drawn thereinto, thereby 65 tightening the brake band 8 upon the nut 7. After this is done the roll may be turned by

the regular driving mechanism, the brake meantime holding the nut in fixed position, and thereby the latter member may be readily tightened or loosened upon the roll. Set screws 12 extend laterally through the nut, 70 for the purpose of locking it in position after it has been set. In practice, the final tightening and first loosening is accomplished by these set screws. This because it is inadvisable to run the nut 7 down too 75 tight. If that be done it is very difficult to loosen it, owing to the large surface contact with the roll body. The set screws are therefore used to give the final tightening and they may be readily loosened, whereupon the nut can be released by the brake. 80

This invention is chiefly directed to the use of three parallel series of cooperating segments, the outer series overhanging and locking in place the intermediate series, and the three series cooperating to form a single groove. Important modifications are shown, but the form just above referred to will be first described. It is very clearly illustrated in one form in Fig. 1. Referring to it, and to the left upper portion of that figure, it will be seen that a rectangular groove 13, constituting one-half of a square is formed by outer segments 14 and 15, and intermediate segments 16. The segments 14 and 15 are identical, except that they are turned in opposite directions so as to have corresponding edges oppositely disposed. The segments 14 and 15 are formed with inner faces 17 and 18 respectively, curved so as 100 to seat securely upon the cylindrical roll body 1. Their opposite outer curved faces are of course cylindrical and concentric, so as to be normally formed portions of the cylindrical exterior face of the composite 105 roll itself. The segments 14 and 15 have inner straight faces 19 and 20, adapted to form the sides of the groove 13, the bottom of which is formed by the exterior faces 21 of intermediate segments 16. The segments 110 14 and 15 have beveled outer sides 22 and 23, opposite faces 19 and 20, respectively. On their inner sides the segments 14 and 15 have the straight faces 19 and 20 above referred to, and below these straight faces 115 the segments are cut away to form beveled undercut side faces 24 and 25, respectively. These beveled faces are adapted to overhang and seat respectively upon correspondingly beveled extensions 26 and 27 of the intermediate segments 16. The beveled face 22 of segment 14 is adapted to lie under and be engaged by the undercut beveled face 5 of the collar member 4. The corresponding beveled face 23 of segment 15 is adapted to 120 be engaged by the undercut beveled face 27 of a slideable ring 28, which fits loosely upon the roll body 1, being slipped thereon before the nut 7 is positioned. The ring 28 is backed by the straight sided slideable ring 130

29, made of a metal of a high coefficient of expansion, and adapted to take up any looseness of the parts that might develop in heating as is known in the art and described in 5 my patent above noted.

The roll may be completed by use of only the parts above described, or a second groove 13^a may be formed thereon by means of a corresponding but oppositely turned undercut ring 30, segments 14^a and 15^a, similar in 10 all respects to segments 14 and 15, and intermediate segments 16^a, either similar to the segments 16, or modified as illustrated at the right of Fig. 1, and as described in de- 15 tail below. A third undercut ring member 31 engages the beveled face of the segment 15^a as illustrated, and this ring contacts with and is driven inward upon the roll by the nut 7, as illustrated.

20 The forming segments themselves may be made in different lengths, provided that their length and number be such that when arranged in series alignment they completely surround the roll. I prefer to use comparatively short segments, since the shorter segments are easier to handle, easier to machine, less likely to break in use, seat more securely upon the roll, and are less expensive to replace individually in case there should be a 25 defect or breakage at any point. When all of the segments are placed together as shown in Fig. 1, similar segments are placed in alignment to form a series extending entirely around the roll as illustrated. The 30 lengths of the segments are so chosen that they seat directly upon the roll body, and are not supported end to end arch-forming. Each of the outer segments is clamped securely against the roll body by means of an 35 overhanging member, and this overhanging compression is made of any desired tightness by driving the nut 7 inward upon the roll body, and then tightening the set 40 screws 12.

45 While the shorter segments are preferred, it is possible to use them in longer lengths. A modification comprising rings cut through at one place, so as to permit forcing firmly to a seat on the roll, may be used in certain 50 cases. These rings are slid on from the end of the roll, and held in position by overhanging faces, as above described.

The outer series of segments 14 and 15 overhang and abut directly against the intermediate series of segments 16, so that the 55 three are held rigidly together and against the roll body.

In the particular form shown at the left of Fig. 1, these segments are arranged to 60 roll a square, the bar lying upon one of its faces. Ordinarily a square is rolled upon its corner, V-shaped grooves being machined in the face of a solid roll. When such 65 grooves have become worn so that the groove edges have to be re-machined, it is necessary

to turn down the entire face of the roll and then to re-cut the groove. This forms a smaller roll and requires adjustment of the housing and driving mechanism. In the 70 form illustrated, when the corners of the segments 14 and 15 wear, these segments may be removed, the faces 19, 20, 24, and 25 machined down so as to restore the sharp corners, and replaced. The metal removed simply allows the segments to move closer 75 together, but the size of the groove and size of the roll will be unchanged. The segments of the cooperating rolls are dressed at the same time and to the same extent, so that the only effect is the moving of the 80 groove as a whole slightly to the left, and no adjustment of the housing or driving mechanism is necessary.

Wear in the intermediate section 16 will be comparatively slight as compared to that 85 of the meeting corners of segments 14 and 15. However, the face 21 of the intermediate segments 16 may be readily machined down to restore it to its original circular form. This would make the groove slightly 90 deeper, and if this enlargement is objectionable, the faces 26 and 27 of the intermediate segments may be dressed down a distance equal to the amount that has been taken off the face 21, and a liner member positioned 95 under the segments 16, extending entirely around the roll body, and so building them up to their original height and thereby maintaining the exact size of the grooves. An additional filler section is inserted to 100 fill up the resulting gap between segments. I have described and claimed such a construction for expanding the size of my forming segments in my co-pending application Serial No. 576,491, filed July 21, 1922. 105

At the right of Fig. 1 an arrangement is shown comprising modified intermediate segments 16^a. These segments are illustrated in greater detail in Fig. 2, wherein are shown transverse teeth 32, in the forming face of these intermediate segments. As 110 will be seen by Fig. 2, such an arrangement of segments with cooperating rolls forms a bar 33 having transverse ribs or teeth 34 thereon. Quite obviously one of the rolls 115 1 or 1^a of Fig. 2 may be provided with smooth faced intermediate segments 16, instead of channelled intermediate segments 16^a, and in that case the bar produced by the rolls would have three plain faces and 120 teeth upon the fourth side. Consequently, it is possible to roll a rectangular bar having three plain faces, and rack teeth upon the other. Or teeth may be provided upon both sides, as illustrated in Fig. 2. 125

In Fig. 3 a modification is shown in that the intermediate sections 16^b are provided with serrations 35, thus producing a bar 33^a 130 which has two plain faces and two opposite faces formed with transverse serrations 36.

Such forms are valuable in concrete reinforcement construction, and also in certain forms of cutting machines.

In Fig. 4 there is illustrated a modification in that the segments 16^c are provided with indentations 37, which produce raised lugs or projections 38 upon opposite sides of the bar 33^b. Here again the construction can be readily varied to produce a projection upon only one side, or to produce the projections 38 upon two opposite sides of a bar. These indentations may be arranged in staggered order, of various forms, and of any desired closeness, as will be obvious. Instead of indentations conical projections may be provided on the face of the segments, which will form indentations on the bar. A great variety of such forms may be rolled, due to the fact that the intermediate segments employed are very easily handled and machined so that the face 21 may carry any desired configuration that will clear itself from the hot metal. This will be readily understood by those familiar with the art. In Fig. 8 a cross-section at right angles to that of Fig. 4 is fully detailed.

In Fig. 5 a modification is shown in that the intermediate segment 16^d extends out flush with the other segments, and two forming grooves 13^b and 13^c are cut at the meeting edges of the respective segments, 14^b, 16^d and 15^b. The shape of the particular groove formed is not a part of the invention, but for the purpose of illustrating the variety of grooves possible with the present invention I have illustrated grooves 13^b as adapted to form a round, and 13^c as adapted to form a diamond-shaped or square bar. Quite obviously the grooves may be of any particular form capable of being made between segments. Or they may be of the same form in different sizes, for making a first and second pass of the same stock, or they may be made of exactly the same shape and size, and one groove used until it is worn out, then the next groove, etc., then the segments removed and the grooves re-dressed.

The outer segments 14^b and 15^b are illustrated in Fig. 5 as narrower than the segments 14 and 15 of Fig. 1. This, because, for use with a standard roll body it is desirable that the three segments 14^b, 15^b and 15^b occupy the same space longitudinally upon the roll as the segments 14, 15 and 16. It is desirable to have segment 16^d wider than the segment 16 so as to space the grooves 13^b and 13^c wider apart, and this accounts for the reduction in width of segments 14^b and 15^b. However, if only one combination of segments is to be applied to the roll, or if a longer roll body is used, the standard segments 14 and 15 may be used instead of the segments 14^b and 15^b, the only change being in the dressing off of the cor-

ners to form the grooves. It will be observed that in large measure corresponding parts are interchangeable in the forms shown.

In Fig. 6 there is illustrated a combination of three series of segments adapted to roll a standard I-beam. When the outer segments 14^e and 15^e become worn at their corners these may be removed and re-dressed upon their two inner groove-forming faces, as above described with reference to the segments 14 and 15. When the intermediate segments 16^e become worn past use they may be removed and replaced with new ones at a much smaller expense than if all of the parts had to be replaced. I may use a construction such as that illustrated in Figs. 10 and 11, wherein the intermediate segments are divided in the middle, forming two exactly similar cooperating segments 16^f and 16^g. Normally these segments are placed back to back as shown in Fig. 10. But when the grooves have become so worn that their forming faces have to be re-dressed, the faces 21^a and 21^b may be machined off to produce the desired groove face, the beveled faces 26^a and 27^a cut down a corresponding amount, which restores the groove to its former size, and then an annular washer member 40 inserted between the segments 16^f and 16^g, as illustrated in Fig. 11. This washer is in thickness twice the amount that has been taken off of each outer face of the segment, and consequently it restores the groove to its original position by expanding the segments internally an amount equal to that which has been taken off on their outer faces. If the upper face of any of the segments have to be re-dressed this may be done without reducing the roll body by inserting a lining member thereunder around the roll, as above referred to in connection with my co-pending application Serial No. 576,491.

In Fig. 9 there is illustrated still another modification in that two series of intermediate segments 16^h and 16ⁱ are provided, with a groove 13^h at their meeting edges, and other grooves 13ⁱ and 13^h at the meeting edges of the outer segments 14^f and 15^f. This modification also serves to illustrate the flexibility of the arrangement of three or four cooperating interlocking segments. Four segments can thus form three grooves either of different shapes, or different sizes of the same shapes, or all identical, with great advantage, as will be readily apparent to those familiar with the art.

The outer segments in all cases are substantially similar, except only for width and the particular groove face machined in their edges. Likewise the intermediate segments 16^f, 16^g, 16^h, and 16ⁱ are the same except for the forming grooves cut therein. Also the intermediate segments 16, 16^f, 16^h, and 16^g are similar except for machining down

their forming faces. Consequently, the various segments for making up the combinations illustrated may be cast or forged in standard units, and dimensions. These may 5 then be machined to the particular use desired, and interchangeable parts made up with a minimum of expense.

I claim:

1. A composite roll comprising a body member, three or more cooperating parallel series of removable facing segments adapted to be seated and retained on the body member, the two outer series of segments having undercut portions adapted to extend 15 over and engage cooperating lateral extensions of adjacent intermediate segments.
2. A composite roll comprising a body member, removable facing segments adapted to be seated and retained thereon, said segments being arranged in cooperating parallel series, the two outer series of segments having undercut portions adapted to extend over and retain cooperating beveled edges of intermediate segments.
3. A composite roll comprising a body member having an undercut fixed retaining collar and an undercut ring thereon, removable forming segments adapted to seat upon the roll body, and to be arranged in not 25 less than three parallel series, the two outer series of segments having their outer faces respectively engaged and retained by the overhanging collar and the undercut ring positioned upon the roll body, the inner 30 faces of the outer segments being partially undercut, the outer faces of the intermediate segments having a portion adapted to extend under and be retained by the undercut portion of the outer segments, whereby all 35 of the segments are clamped against the roll body and against each other.
4. A composite die forging roll comprising a body member, three or more cooperating parallel series of segmental facing members adapted to be seated and clamped 45 on the body member and to form a groove between the meeting edges thereof, and means to clamp the segments against each other and against the roll body.
5. A composite die-forging roll comprising a body member, removable facing segments having beveled edges and adapted to seat on the body, overhanging means engaging said beveled faces and clamping the 50 segments together and against the roll body, said segments being arranged in three parallel cooperating series, and forming a groove between the longitudinal meeting edges of the segments.

6. A composite die-forging roll comprising a body member and removable forming segments adapted to be seated and clamped upon the body member, said forming segments being arranged in three parallel cooperating series, the outer series forming 60 the sides of a groove and the intermediate series forming the bottom of a groove.

7. A composite roll comprising a body member and removable forming segments adapted to be seated and clamped upon the 70 body member, said forming segments being arranged in three parallel cooperating series, the outer series forming the sides of a groove and the intermediate series forming the bottom of a groove, the intermediate segments 75 being retained against the body member by overhanging portions of the outer segments.

8. A composite roll comprising a main body member, facing members formed in series of similar segments, said facing members being arranged in three cooperating series, the outer series having their outer faces beveled, overhanging means to engage these beveled faces and to clamp the segments against the roll body, the intermediate series of segments being overhung and clamped against the roll body by the outer series of segments, and a groove formed between the segments and extending around 80 the composite roll.

9. A composite roll comprising a roll body, removable facing segments retained upon the roll body, said segments being arranged in three cooperating series with a groove formed between the three series of 95 segments, the outer segments forming the sides of the groove and the intermediate segments forming the bottom thereof, the forming face of the intermediate segments being adapted to forge a special configuration on 100 one side of a bar formed in the groove.

10. A composite roll for die-finishing bars, comprising a body and removable segments adapted to seat on the body and to be clamped thereon, said segments being arranged in not less than three parallel series, two outer series of segments forming the sides of a groove and intermediate series of segments forming the bottom of the groove, the outer segments having overhanging portions for engaging and retaining the intermediate segments.

In testimony whereof, I sign my name.

GEORGE BAEHR.
